UNITED STATES PATENT OFFICE

98,885

DESIGN FOR A CAMP STOVE

Charles L. Pearson, Buffalo, N. Y., assignor to
Master Metal Products, Inc., Buffalo, N. Y., a
corporation of New York

Application January 29, 1936, Serial No. 60,880

Term of patent 3½ years

To all whom it may concern:

Be it known that I, Charles L. Pearson, a citizen of the United States, residing at Buffalo, in the county of Erie and State of New York, have invented a new, original, and ornamental Design for Camp Stoves, of which the following is a specification, reference being had to the accompanying drawing, forming a part thereof.

Figure 1 is a perspective view of the camp stove embodying my design. Figure 2 is a rear view of the same, on a reduced scale.

I claim:

The ornamental design for a camp stove, substantially as shown.

CHARLES L. PEARSON.
